L. E. CLARK

WRENCH

Filed Oct. 18, 1921

Luther E. Clark. Inventor

By

Herbert E. Smith

Attorney

UNITED STATES PATENT OFFICE.

LUTHER E. CLARK, OF LACROSSE, WASHINGTON.

WRENCH.

Application filed October 18, 1921. Serial No. 508,566.

To all whom it may concern:

Be it known that I, LUTHER E. CLARK, a citizen of the United States, residing at La-crosse, in the county of Whitman and State 5 of Washington, have invented certain new and useful Improvements in Wrenches, of which the following is a specification.

My present invention relates to improvements in wrenches of that type involving the use of a fixed jaw, a slidable, adjustable jaw and frame, and the utilization of a rack and sliding rack catch, together with spring devices for seating the slidable jaw and frame and also the rack catch.

The primary object of the invention is the provision of a tool of this character which is comparatively inexpensive in cost of production, involves a practical minimum number of parts, which may with facility be adjusted for use, and which is durable and proficient in service.

The invention consists in certain novel combinations and arrangements of parts as will be hereinafter fully explained and pointed out in my appended claim.

In the accompanying drawings I have illustrated one complete example of the physical embodiment of my invention wherein the parts are combined and arranged according to the best mode I have thus far devised for the practical application of the principles of my invention.

Figure 1 is a view in elevation of a wrench embodying my invention, parts being broken away to disclose the construction of parts.

Figure 2 is a transverse sectional view at line 2—2 of Fig. 1.

Figure 3 is a sectional view of Fig. 1 at line 3—3 of that figure.

Figure 4 is a sectional view of the spring supporting bushing located within the wrench shank.

In the preferred form of the invention as illustrated in the drawings the fixed jaw 1 is integral with the hollow shank 2, and the slidably adjustable jaw 3 is integral with the slidable frame 4 which encloses a portion of the shank, both the shank and frame 50 being rectangular in cross section, as indicated in Fig. 2.

The slidable jaw and its frame are provided with a stem 5 located within the hollow shank and the stem is secured to the 55 perforated lug 6 which extends laterally of the frame and projects through an open side

of the shank, in order that the stem may be located in the longitudinal center of the hollow stem. This lug forms an additional guide means in conjunction with the frame 60 4 for guiding the movement of the movable jaw and its frame while the latter is being adjusted and aids in holding the jaw in proper position.

The movable jaw is normally pressed toward the fixed jaw by a tension spring 7 that is coiled about the stem 5 and interposed between the lug 6 at one end and the supporting bushing 8 at its other end. This bushing is located within the hollow shank 70 and provided with a stud 9 having a head 10, and the stud projects through and is slidable in the longitudinally extending slot 11 in the tool shank. At its ends this slot is provided with notches 12 and 13, the 75 notch 12 being adapted to receive the stud 9 to support the bushing in position as indicated in Fig. 1, while the notch 13 is adapted to receive the stud 9 when the spring action is released. Thus in Figure 80 1 the spring is contracted between the bushing 8 and lug 6 and the spring urges the movable jaw toward the fixed jaw. To release the spring, the bushing is turned, the stud 9 is turned with it and the tension of 85 the spring forces the bushing toward the end of the shank, and then by turning the stud 9 into the notch 13 the bushing is retained in this position with tension relieved from the spring. With the spring tension 90 released the movable jaw and frame may be pushed toward the fixed jaw by hand for adjustment.

For adjusting the spring pressed movable jaw the thumb or finger is pressed against 95 the horn 14 which is integral with and projects from the jaw frame 4 and by pressure thereon the movable jaw may be moved away from the fixed jaw against the tension of the spring 7.

In connection with the adjustable spring pressed jaw I utilize a sliding rack catch or pawl 15 which co-acts with the rack bar 16 fixed within the shank 2 to prevent the movable jaw being forced away from the 105 fixed jaw. This pawl or rack catch is pivoted at 17 in the movable frame and the spring 18 within the frame bears against the trigger 19 forming one arm of the pawl, to hold the pawl in contact with the rack 110 bar.

Assuming the parts of the tool to be in

position as shown in Fig. 1 the operation of the device is as follows. To adjust the slideable jaw away from the fixed jaw, pressure of the thumb or finger is applied to the thumb piece 14 and at the same time the thumb may be slightly turned to press against the trigger 19. The trigger is thus moved against the spring 18 to release the pawl 15 from its rack bar 16, and the frame 10 is now free to be moved against tension of the spring 7 for adjusting the movable jaw. In adjusting the tool to engage a bolt or nut the movable jaw is adjusted to approximate distance and then the jaws passed over the object; pressure on the thumb piece 14 is then released permitting the spring 7 to exert its pressure against the movable jaw, and the jaw is closed over the object. The rack catch 15 is also released and thus en-

gages with the rack bar 16 to hold the movable jaw in rigid relation to the fixed jaw, and the tool may be manipulated in usual manner.

Having thus fully described my invention, what I claim as new and desire to secure by Letters Patent is—

The combination with the fixed jaw and hollow shank having a slot and a pair of notches therein, of a movable jaw and integral frame, a stem on the frame, a spring on the stem, a bushing within the shank to support said spring, said bushing having a stud slideable in the slot to engage either of said notches, a rack bar, and a spring pressed rack catch.

35 In testimony whereof I affix my signature.

LUTHER E. CLARK.
